MARKER LIGHT FOR HIGHWAYS OR THE LIKE

Frank I. Fuller, Menlo Park, and Montgomery C. Swezy,
Palo Alto, Calif., assignors to Western Progress Manufacturers,
Palo Alto, Calif., a partnership

Application July 22, 1957, Serial No. 47,022

Term of patent 14 years

(Cl. D72—1)

FIG. 1

FIG. 2

Figure 1 is a front elevational view showing of a marker light for highways or the like showing our new design; and

Figure 2 is a side elevational view thereof.

The rear and side of the marker light for highways or the like not shown are substantially the same in appearance as the views shown.

We claim:

The ornamental design for a marker light for highways or the like, substantially as shown and described.
